CLAIM

We claim the ornamental design for an insert for partition panel, as shown and described.

DESCRIPTION

FIG. 1 is a perspective view of an insert for partition panel showing our new design;

FIG. 2 is a front view thereof;

FIG. 3 is a side view thereof, the opposite side being a mirror image;

FIG. 4 is a top view thereof, the bottom view being a mirror image;

FIG. 5 is a perspective view of a second embodiment of an insert for partition panel showing our new design;

FIG. 6 is a front view thereof;

FIG. 7 is a side view thereof, the opposite side being a mirror image;

FIG. 8 is a top view thereof, the bottom view being a mirror image;

FIG. 9 is a perspective view of a third embodiment of an insert for partition panel showing our new design;

FIG. 10 is a front view thereof;

FIG. 11 is a side view thereof, the opposite side being a mirror image; and,

FIG. 12 is a top view thereof, the bottom view being a mirror image.

The dashed lines shown in FIGS. 1-12 are to show the environment and do not form a part of the present invention.
